By Osney & Bair Atty's.

UNITED STATES PATENT OFFICE.

EDGAR E. McVICKER, OF OMAHA, NEBRASKA.

SLIDE-POCKET FILM-CASE.

1,262,965.

Specification of Letters Patent. Patented Apr. 16, 1918.

Application filed October 25, 1917. Serial No. 198,508.

To all whom it may concern:

Be it known that I, EDGAR E. McVICKER, a citizen of the United States, and resident of Omaha, in the county of Douglas and State 5 of Nebraska, have invented a certain new and useful Slide-Pocket Film-Case, of which the following is a specification.

My invention relates to slide pockets for film cases holding a slide.

10 The object of my invention is to provide a pocket for holding a slide in a film case, so that the slide may be thoroughly protected.

With these and other objects in view my invention consists in the construction, arrangement and combination of the various parts of the device, whereby the objects contemplated are attained, as hereinafter more fully set forth, pointed out in my claim, and illustrated in the accompanying drawings, 20 in which:

Figure 1 shows a perspective view of a slide pocket film case embodying my invention.

Fig. 2 shows a plan view of the blank 25 from which the slide pocket is made.

Fig. 3 shows a vertical, sectional view through the wall of the film case and slide pocket.

It is well known that moving picture films 30 are shipped in cases such, for instance, as that shown in the accompanying drawings, and comprising a box or receptacle indicated by the reference character 10.

The ordinary film case has a hinged cover 35 11 provided with a peripheral flange 12 designed to extend downwardly over and overlap the upper edge of the film case proper.

It is the custom in the film exchange business for agencies or film distributers to send 40 to the theater owner or operator, a few days before any certain film is to be exhibited, a slide which is of suitable transparent material, advertising feature films which are to be later exhibited by the theater manager.

45 These slides are packed in various ways and are sent by mail or express and are very frequently broken or lost.

It has, therefore, been my purpose to provide in connection with the film case, such 50 as that herein shown, a slide pocket which can be made mounted on a part of the film case for holding the slide.

Where a film is shipped on one day there can be sent with it the slide advertising another film to be shipped and use a few days 55 later.

The film cases are usually made of sheet iron and my improved slide pocket is preferably also made of sheet iron or other suitable material, and may be made from a 60 blank 13, substantially rectangular in general outline.

The blank 13 has at its outer end a slot 14 to permit access to the thumb or finger, and at its lower end an extension 15, which is of less length from side to side than the total width of the blank. 65

At one side edge of the blank 13 a strip 16 is bent along the line 17 at right-angles to the body of the blank. 70

At the opposite side edge a strip 18 is bent in the opposite direction along the line 19. At the edge of the strip 18, a strip 20 is bent to position lying in a plane parallel with the plane in which the body of the blank 75 13 lies. The extension 15 is bent horizontally to position for forming a bottom to the box.

The strips 18 and 20 are formed with holes 21 to receive rivets, screws or the like. 80

The pocket formed from the blank is placed on the inside of the film case 10 with the strip 16 against one end of said film case, and with the strip 20 against one side of the film case. The strips 16 and 20 are securely 85 fastened to the film case walls by means of rivets 22.

The upper edge of the pocket is arranged substantially flush with the upper edge of the film case, and the upper edge of said 90 film case may, if desired, be provided with a notch 23, which registers with the notch 14.

It will thus be seen that the wall of the film case 10, and the parts of the formed up pocket, as above described coöperates 95 and forms a compartment or receptacle of proper size to hold a slide.

The flange 12 of the cover of the film case fits down over the edge of the case when the cover is closed covering the top of the film 100 pocket and the notch 23 where the latter is used.

The extension 15, as shown in Fig. 2, forms the bottom of the pocket.

A device of this kind has a large number 105 of advantages over the means now in use for handling the slides. Among others the slide pocket affords a safe shipping means for the slide, which prevents the destruction and loss thereof during shipment. 110

Insomuch as the distributer is sending frequent shipments to the exhibitor, the slides

can be shipped with the films, so that the distributor is saved the express expense now necessary where the slides are separately shipped.

Furthermore the distributor is saved the expense of using destructive wooden boxes or the like for packing the slides.

Changes may be made in the construction and arrangement of the parts of my improved device without departing from the essential features and purposes thereof, and it is my intention to cover by the claim of the patent to be issued on my present form of construction any use of mechanical equivalents which may be reasonably included within the scope of my claim.

I claim as my invention:

In a device of the class described, a receptacle designed especially for receiving films, said receptacle having an angular corner, a

slide receiving pocket comprising a flat member spaced from one of the walls of said receptacle adjacent to said corner having at one side edge an off-set portion terminating in a flange secured to one wall of said receptacle, and having at its opposite side edge a flange designed to fit against and secured to another wall of said receptacle, and having a bottom member, said first described member of the slide pocket having its upper edge substantially flush with the top of one wall of the receptacle, said last mentioned member and the adjacent wall having in their upper edges registering slots, and a hinged cover for said receptacle having a downwardly extending flange adapted to fit over and cover said slots.

Des Moines, Iowa, August 4, 1917.

EDGAR E. McVICKER.
